UNITED STATES PATENT OFFICE

164,442

CONFECTION PACKAGE

Mary P. Park, Chester County, Pa.

Application February 27, 1951, Serial No. 14,325

Term of patent 3½ years

(Cl. D58—2)

To all whom it may concern:

Be it known that I, Mary P. Park, a citizen of the United States, residing in the county of Chester, in the Commonwealth of Pennsylvania, have invented a new, original, and ornamental Design for a Confection Package, of which the following is a specification, reference being had to the accompanying drawing, forming part thereof:

Fig. 1 is a front view of the package, comprising throughout non-edible material.

Fig. 2 is a rear view.

Fig. 3 is a side view.

I claim:

The ornamental design for a confection package, as shown.
